UNITED STATES PATENT OFFICE.

ARTHUR LEWIS BREITENSTEIN, OF AKRON, OHIO, ASSIGNOR TO THE RUBBER PRODUCTS COMPANY, OF BARBERTON, OHIO, A CORPORATION OF OHIO.

DESIGN FOR AN ELASTIC VEHICLE-TIRE.

48,926.

Specification for Design.

Patented Apr. 25, 1916.

Application filed December 27, 1915. Serial No. 68,963. Term of patent 14 years.

To all whom it may concern:

Be it known that I, ARTHUR LEWIS BREITENSTEIN, a citizen of the United States, and a resident of Akron, Summit county, Ohio, have invented a new, original, and ornamental Design for Elastic Vehicle-Tires, of which the following is a specification, reference being had to the accompanying drawings, forming part thereof.

In the drawings, Figure 1, is a view in side elevation of an elastic vehicle tire, showing my new design; and, Fig. 2, is a transverse sectional view taken approximately on line II, II.

I claim:—

The ornamental design for an elastic vehicle tire, as shown.

ARTHUR LEWIS BREITENSTEIN.
